UNITED STATES PATENT OFFICE.

FRANKLIN G. PECK, OF HONOR, MICHIGAN.

VENEER PACKAGE.

1,254,430.

Specification of Letters Patent. Patented Jan. 22, 1918.

Application filed August 14, 1914. Serial No. 856,731.

To all whom it may concern:

Be it known that I, FRANKLIN G. PECK, a citizen of the United States, residing at Honor, in the county of Benzie and State 5 of Michigan, have invented new and useful Improvements in Veneer Packages, of which the following is a full, clear, concise, and exact description, reference being had to the accompanying drawing, forming a 10 part of this specification.

My invention relates to improvements in veneer packages or shipping containers, and more particularly to those of cylindrical form.

15 One object of my invention is to provide a package so constructed as to permit of the use of relatively narrow strips of veneer as distinguished from the wide sheets once available, but now becoming more and more 20 difficult to obtain. Another object is to provide a package which shall not only be as satisfactory structurally as more expensively constructed prior devices, but which shall remain tight despite the inevitable 25 warping and twisting of the wood, and thereby serve efficiently for the shipment of granulated or pulverized commodities.

In the accompanying drawings, I have 30 illustrated a construction which embodies my invention. Figure 1 is a side elevation thereof partly in section. Fig. 2 is a section on the line 2—2 Fig. 1. Fig. 3 is an enlarged sectional view of certain details.

Generally speaking, the wooden packing 35 drum or barrel, which is cylindrical in form, comprises an outer veneer made up of several sheets or strips with the grain running longitudinally, that is, parallel to the axis of the cylinder, and an inner veneer 40 made up of strips, the grain of which runs at right angles with respect to said axis. The outer veneer consists of a plurality of substantially, parallel, curved strips 1 which are made preferably of maple veneer 45 about one-sixteenth of an inch thick. These strips are relatively wide, and are arranged with their edges fairly close together, although it is not essential that they meet accurately. This outer veneer is bound and 50 reinforced by a plurality of hoops 2. The inner veneer consists of a plurality of relatively narrow strips 3 which are bent into completely closed circles, the ends overlapping each other as shown in Fig. 2. The 55 edges of these strips are fairly close together, but need not match each other accurately,

the cracks being covered by gummed strips of paper 4 which adhere to the adjacent strips. The gummed paper is applied to said strips before they are bent, thereby 60 forming a flat sheet of veneer, having a width approximately equal to the height of the finished barrel or cylinder. Said sheet is thereafter rolled into circular form, and the outer veneer and hoops simultaneously 65 applied thereto to reinforce it.

In Figs. 1 and 3, the thickness of the various parts is somewhat exaggerated to render the drawing a little clearer. It will be understood, however, that the paper strips are 70 so thin that the outer and inner cylinders are practically in contact, notwithstanding the interposition of the paper between them. While in these figures (Figs. 1 and 3) a crack is shown between said outer and inner 75 cylinders, it, in practice, does not exist.

The strips 3, while they are made preferably of maple, need not necessarily be made of this wood, as gum wood or other cheap substitutes may be employed. Said strips 80 in any case are more or less irregular before bending into circular form, and are liable to warp and twist. The paper strip, however, is sufficiently strong to hold said strips together despite such warping and twisting; 85 and after they have once been rolled into cylindrical shape, the interior surface is comparatively smooth and regular. During long, continued use, however, the individual strips shrink, warp and otherwise distort 90 themselves, tending to open the cracks between the adjacent strips whereby the commodity within the package would sift out were it not for the paper which covers the cracks, adheres to the wood adjacent thereto 95 and forms a lining between the inner veneer and the outer veneer. The paper furthermore being flexible, permits of considerable distortion in this respect. If a single sheet of inner veneer were employed, the warping 100 and distortion would result in opening cracks unless a good grade of maple were employed. Furthermore, the scarcity of good stock in such great widths as would be required, renders such use prohibitive in 105 most cases. Where a plurality of parallel strips are employed, however, the distortion is more or less local and does not affect the overall dimensions, particularly in view of the fact that there are a number of cracks 110 any one of which may open or close more or less, without affecting the tightness of the

inner veneer since the cracks are covered with the paper strips, and without modifying the aggregate width of said strips.

Owing to the difficulty and expense of obtaining maple in sheets wide enough to form the inner veneer of a single bent-over sheet, and owing also to the difficulty of maintaining other wide veneers in cylindrical form without slitting, cracking and other distortion excessive in degree, the advantages of a construction wherein the individual strips of veneer may be employed will be readily apparent.

The overlapping ends of the strips 3 are preferably nailed to each other through the outer veneer and the hoops as indicated at 5, and the ends of the hoops are also nailed together and nailed through both layers of veneer as at 6, preferably nearly opposite the point where the ends of strips 3 are nailed. The overlapping ends of the hoops 2 are tapered or beveled so as to avoid excessive thickness, the outer tapering ends being reinforced by suitable metal bands 7.

An inner hoop or liner 8 is suitably secured near each end of the barrel against which the two heads 9 are located, each of the latter being held in place by a second outer hoop 10.

With the improved construction above described, a very light, strong package results which meets all modern requirements, and at the same time, prevents leakage of powdered or granulated material such as sugar for example. Cylindrical packages constructed in the manner above described, are strong enough to be used satisfactorily for a shipment of several hundred pounds of iron in extreme cases, although not ordinarily subjected to such severe service.

In view of the restrictions and regulations adopted by the railroads, and approved by the Inter-State Commerce Commission, the construction of shipping packages of various kinds is limited in many ways so that in order to satisfactorily meet the conditions, either very expensive grades or widths of veneer must be employed, or else such an excessive thickness used as to render a package bulky.

The invention is not to be limited to all

the details of construction described and illustrated, as various changes may be made therein without departing from the spirit of the invention as expressed in the appended claims.

Having thus described my invention what I claim as new, and desire to secure by Letters Patent of the United States is:

1. A cylindrical shipping container comprising an inner cylinder composed of a plurality of relatively narrow strips of veneer, each formed as a closed hoop and arranged side by side, tape overlapping adjacent edges of said strips, and covering the cracks between said edges and an outer cylinder with the grain at right angles to the grain of the inner cylinder, for reinforcing the latter and backing up said tape.

2. A veneer package comprising a plurality of curved strips of veneer having their edges joined by an adhesive fabric and their ends overlapping, an outer veneer composed of strips arranged at right angles to the inner strips, and hoops surrounding said outer veneer, with their ends overlapping, said overlapping ends being secured to the body of the container at a point substantially opposite the overlapping ends of said inner strips.

3. A cylindrical veneer package comprising outer curved veneer strips arranged with the grain running substantially parallel to the axis of the cylinder, a plurality of reinforcing hoops for said outer veneer, an inner veneer lining for said package consisting of a plurality of cylindrical strips arranged side by side throughout the length of said cylinder, thin flexible material covering the cracks between said adjacent inner strips whereby the latter may be distorted without opening cracks entirely through said package, and heads secured in the opposite ends of said cylinder.

In witness whereof, I have hereunto subscribed my name in the presence of two witnesses.

FRANKLIN G. PECK.
